UNITED STATES PATENT OFFICE.

GEORGE R. BAILEY, OF BROOKLYN, NEW YORK, ASSIGNOR TO STERLING CASKET HARDWARE COMPANY, OF BROOKLYN, NEW YORK, A CORPORATION OF NEW YORK.

DESIGN FOR A CANDLESTICK FOR ALTARS.

50,642.

Specification for Design.

Patented Apr. 24, 1917.

Application filed March 7, 1917. Serial No. 153,193. Term of patent 7 years.

To all whom it may concern:

Be it known that I, GEORGE R. BAILEY, a citizen of the United States, residing at No. 502 Bedford avenue, in the borough of Brooklyn, county of Kings, and State of New York, have invented a new, original, and ornamental Design for a Candlestick for Altars, of which the following is a specification, reference being had to the accompanying drawing, forming part thereof.

Figure 1 is a perspective view of one side of my candle stick, showing one of the four sides of the base thereof; Fig. 2 is a perspective rear view of my candle stick, show-

ing one of the opposite sides of the base thereof; Fig. 3 is a fragmentary perspective view showing the third side of the base of my candle stick and Fig. 4 is a fragmentary perspective view showing the opposite or fourth side of the base of my candle stick.

I claim:

The ornamental design for candle stick for altars, as shown.

GEO. R. BAILEY.
